UNITED STATES PATENT OFFICE.

FIN SPARRE, OF WILMINGTON, DELAWARE, ASSIGNOR TO THE E. I. DU PONT DE NEMOURS POWDER COMPANY, OF WILMINGTON, DELAWARE, A CORPORATION OF NEW JERSEY.

AMMONIUM-NITRATE METALLIC EXPLOSIVE AND PROCESS OF MAKING SAME.

No. 850,267.

Specification of Letters Patent.

Patented April 16, 1907.

Application filed November 28, 1905. Serial No. 289,422.

To all whom it may concern:

Be it known that I, FIN SPARRE, a subject of the King of Norway, residing at Wilmington, county of Newcastle, and State of Delaware, have invented a new and useful Improvement in Ammonium-Nitrate Metallic Explosives and Processes of Making Same, of which the following is a full, clear, and exact description.

10 The object of my invention is to make more sensitive to the cap so-called "safety-explosives," in which the oxygen-carrier is coated with an insensitive "coating."

Most safety-explosives are so insensitive to ignition that they require excessively strong caps and yet frequently do not detonate completely. This is especially the case where the powder or the oxygen-carrier of the powder is provided with a coating. Powders of the above type are so very safe that they can be made somewhat more sensitive to the cap and yet be perfectly safe in handling and transportation.

25 The above objects are attained by my improved process of incorporating the ingredients, the principle of my process being first to incorporate the oxygen-carrier with all the ingredients except the ingredient intended for making the powder more sensitive and 30 providing this mixture with the coating, whereupon the resultant mixture is incorporated with the sensitizing ingredient. The oxygen-carrier may also be coated first and then incorporated with the other ingredients, 35 although this is not advisable unless the powder is composed of only an oxygen-carrier, a coating, and one or more ingredients, together acting as a sensitizing agent. It will thus be seen that the sensitizing agent, 40 being one or more ingredients, ought to be able to detonate without aid of the oxygen-carrier.

One example of my new process procuring my improved explosive is as follows: First, 45 incorporate ammonium nitrate and aluminum or other metallic ingredient to form the ordinary ammonium-nitrate metallic powder, then incorporate the above mixture with a coating or indurating mixture or body in 50 liquid or gelatinous form—such, for instance, as a liquid nitro compound (in which has been dissolved a solid nitro compound) in which is dissolved guncotton, as set forth

in my application filed October 24, 1905, Serial No. 284,152—and then incorporate 55 the last-named mixture with a sensitizing ingredient, such as ungelatinized nitrocellulose, the resultant powder consisting of an ammonium-nitrate metallic composition, a coating ingredient, and a sensitizing ingredient. 60 In carrying out said process the proportions of the several ingredients are preferably as follows: ammonium nitrate, sixty-eight per cent.; aluminium, ten per cent.; coating mixture, twelve per cent.; ungelatinized nitrocellulose, ten per cent.

Another example is as follows: First, incorporate ammonium nitrate (which may or may not have previously been incorporated with other ingredients) and the coating ingredient, and then incorporate the resultant mixture and nitroglycerin, the resultant powder containing ammonium nitrate, nitroglycerin, and the coating ingredient. The proportions of these ingredients are preferably as follows: ammonium nitrate, seventy-five per cent.; nitroglycerin, twelve per cent.; coating ingredient, thirteen per cent. The coating mixture that I prefer to use is that set forth as preferable in my said application, as 80 follows: mononitrotoluol, eighty per cent.; trinitrotoluol, ten per cent.; guncotton, ten per cent.

Having now fully described my invention, what I claim, and desire to protect by Letters 85 Patent, is—

1. The process of making safety-explosives which consists in incorporating an ammonium-nitrate metallic explosive powder with a coating ingredient and then incorporating 90 the mixture with a sensitizing ingredient substantially as described.

2. The process of making safety-explosives which consists in incorporating an ammonium-nitrate metallic explosive powder with a 95 coating ingredient and then incorporating the mixture with ungelatinized nitrocellulose substantially as described.

3. The process of making safety-explosives which consists in preparing a solution of guncotton in a liquid nitro compound to form a coating ingredient, then incorporating a nitrate-of-ammonia metallic explosive powder with the coating ingredient, and then incorporating the mixture with ungelatinized nitrocellulose substantially as described.

4. The process of making safety-explosives which consists in dissolving a normally solid nitro compound in a liquid nitro compound, then dissolving guncotton in the solution, 5 thus forming a coating ingredient, then incorporating a nitrate-of-ammonia metallic explosive powder with the coating ingredient, and then incorporating the mixture with ungelatinized nitrocellulose substantially as 10 described.
5. An explosive composition consisting of

a nitrate-of-ammonia metallic explosive powder coated with a coating ingredient, and ungelatinized nitrocellulose substantially as described.

In testimony of which invention I have hereunto set my hand, at Philadelphia, on this 21st day of November, 1905.

FIN SPARRE.
